UNITED STATES PATENT OFFICE

VINCENT O. VAN BRIGGLE, OF BRIDGEVILLE, PENNSYLVANIA

CARBURETOR

Application filed May 16, 1929. Serial No. 363,527.

This invention relates to carburetors particularly designed for use in connection with motors of the type so generally employed in automobile and motor-boat constructions.

Among the objects of the present invention are, to provide a valve structure for controlling the admission of both a liquid fuel and air to the mixing chamber of the carburetor; to provide a new and improved vacuum controlled valve structure; to provide a construction in which the liquid fuel and air are passed in a downward direction, after their introduction to the carburetor and before reaching the mixing chamber; to provide in the mixing chamber or associated therewith efficient means for vaporization of the liquid fuel, said means disposed in such a manner as to receive the downwardly passing fluids; to provide means whereby the desired carburization or vaporization is effected before entering the combustion chamber of the engine and without the necessity of heating the intake manifold, as is usual.

In the accompanying drawings, which illustrate an application of my invention:

Fig. 1 is a top plan view of a carburetor embodying my invention;

Fig. 2, an enlarged vertical sectional view on the line II—II of Fig. 1;

Fig. 3, a partial view in elevation, particularly showing the manual control means;

Fig. 4, a cross section on the broken line IV—IV of Fig. 3;

Fig. 5, a vertical sectional view on the line V—V of Fig. 1, particularly showing the operating sleeve; and

Fig. 6, a perspective view of the carburetor valve structure.

Referring to the drawings, the carburetor 5 comprises essentially a base portion 6, an upwardly extending cylindrical casing portion 7, and an enlarged head or top portion 8, positioned above the casing 7 by means of spaced-apart connecting ribs 9. The head 8 is formed with a cylindrical opening or bore 10 providing a vacuum chamber *a* to receive a valve structure generally designated A. Casing 7 has a reduced bore 11 in communication with chamber *a* at its top, and in communication with a cylindrical chamber *b* of

the base portion 6. It will be noted that chamber *b* is eccentrically disposed relatively to the axis *x*—*x* of bore 11 and chamber *a*, as will be hereinafter more fully described.

Centrally located with respect to the axis *x*—*x* and integral with the base portion 6, I provide a hollow vertically extending valve post 12, positioned by means of a radially extending rib 13. Said valve post 12 is formed with an opening 14 terminating in a reduced opening 15 at its lower portion to receive a needle valve 16 of the valve structure A.

The needle valve 16 is rigidly secured at its upper end to a piston or disk 17, which is adapted to reciprocate in the vacuum chamber *a*. The diameter of said piston 17 is slightly less than that of the bore of chamber *a* so as to provide sufficient clearance to eliminate friction. The piston 17 is provided with a plurality of openings 18, and a depending cylindrical apron 19 having an outer diameter slightly smaller than that of the bore 11. On the under surface of piston 17, between the apron 19 and the periphery of said piston, is a ring-area *c*, adapted to be acted on by atmospheric pressure. The piston 17 is further provided with a centrally disposed hub 20, the under face of which is adapted to normally contact with a hub 21 of a cylindrical operating sleeve 22.

Said operating sleeve is movable within the bore 11 of casing 7, and is adapted to be manually raised and lowered. To this end, casing 7 for a portion of its circumference is formed with an inclined slot 23. Extending therethrough and secured to the sleeve 22 by a threaded extension 24, I provide a radial pin 25. At its outer end, pin 25 is internally threaded to receive a set screw 26 for securing operating wire 27 in a transverse opening 28. The wire 27 is connected to operating means (not shown) for manual control, as will be readily understood. The sleeve 22 and in turn the valve structure A are normally maintained in the position shown in the drawings, by means of a tension spring 29 secured to the base portion 6.

An apertured lug 30 extends from one side of the base portion 6 to receive a pivotal ter-

terminal 31 of a fluid reservoir 32. Said terminal projects upwardly from the outer end of an inclined arm or bracket 33 integral with the fluid reservoir, and is secured in the opening 34 of the lug 30 by means of a cap screw 35. Such construction permits the fluid reservoir 32 to be moved into different positions to provide a compact unit. The fluid reservoir is of the usual construction, and includes a needle valve 36 operated by a float 37, to control the admission of the fluid from a supply pipe 38 and maintain the fluid at a certain level, as indicated by the line $h-h$ of Fig. 2. The bracket 33 is provided with a fluid port 39 terminating within the opening 34 and communicates with a fluid pot 40 extending upwardly through the rib 13 of base portion 6 for the admission of fluid to the needle valve 16.

Vacuum chamber a is closed by means of a top 41 secured to the head 8 by screws 42. The chamber b is closed by a heating unit generally designated B, secured to the base portion by means of screws 43. The eccentric relation of the chamber b to the axis of the valve structure described permits the positioning of an inclined heating and vaporizing plate 43 of the heating unit in a communicating chamber 46; thus allowing an end of the plate to come directly under the needle valve and casing and the fluid to pass by gravity over said plate. From the construction described, it will be noted that chamber b , together with chamber 46, constitutes the mixing chamber of the device and that the liquid fuel and air are passed downwardly into said mixing chamber before mixing.

Plate 43 is provided with staggered upwardly-extending projections 44 to produce a turbulence and maintain the fluid in contact with the heating surface until it becomes vaporized. Heat is introduced under the plate 43 from the exhaust manifold of the engine to which it is applied and passes through a passage 45, and thence to the exhaust pipe. Such circulation will be readily understood by those skilled in the art. The chamber 46 terminates in a throttle chamber 47 which is adapted to be connected with the intake manifold 48 of the engine (not shown) by means of flanges 49 and studs 50.

Disposed on a transverse shaft of said chamber 47, I provide a control or throttle valve 51 in the form of a bent disk inserted in a slot in said shaft and secured thereto in any suitable manner. Said valve is adapted to be opened by a counter-clockwise rotation (see Fig. 2) and has its lower portion d slightly inclined in the direction of rotation. This construction provides a greater opening at all times, which produces a friction by the passage of air thereunder and lifts the mixture into the air, whereby it is carried into the intake manifold 48 and thence to the cylinders of the motor.

In operation, the throttle 51 is opened and the engine turned over, thus creating a vacuum in the carburetor; said vacuum is transmitted to chamber a through openings 18. Atmospheric pressure acting on the ring-area c of piston 17, raises the valve structure A a slight amount, thereby raising valve 16 and permitting liquid fuel to be drawn from reservoir 32 through ports 39 and 40, and flow downwardly over heating and vaporizing plate 43 by gravity action until vaporized by action of the projections 44 and the incoming air passing downwardly thereover.

When valve structure A is raised, apron 19 raises from sleeve 22, permitting atmospheric air to flow downwardly around the valve post 12 to mix with the liquid fuel on the plate 43. The action just described effects a "floating" of the valve structure A, whereby the correct amount of air is introduced to mix with a corresponding amount of fluid.

When the motor is to be speeded up, the opening at the valve 51 is increased. The increase of suction tends to draw a greater volume of air through the opening between the apron 19 and sleeve 22, and decreases the pressure in chamber a , whereby the atmospheric pressure on area c raises the valve structure A, permitting a greater amount of fluid to be drawn in through opening 15. The parts then become balanced as before, with the increased flow of air and fluid in their proper proportion, passing downwardly over plate 43 and into the engine.

To choke the carburetor, as when starting a cold engine, a pull on the wire 27 will operate sleeve 22, hub 21, and raise piston 17 and its needle valve 16 manually to increase the opening for the passage of fluid.

In the drawings, the normal or idling position of the carburetor is shown. Apron 19 and sleeve 22 are spaced apart slightly to permit enough air to enter for idling speed of the engine. Also, the sleeve 22 and piston 17 are raised slightly, as is needle valve 16, by means of set screw 52 threaded within a boss 53 of casing 7 immediately adjacent the slot 23. Said screw contacts with pin 25 and provides an idling adjustment for the carburetor.

When a richer mixture is desired, raising sleeve 22 by means of wire 27, will increase the volume of fluid without increasing the amount of air. The opening between apron 19 and sleeve 22 is dependent upon the speed of the motor, as hereinbefore described, and, hence, raising sleeve 22 will effect a raising of piston 17 and its needle valve 16, admitting a greater amount of fluid for the same volume of air.

It will be noted that a small opening 54 extends from the face of flange 49 to a point to the rear of throttle valve 51 in chamber 47. Also a transverse opening 55 is in communication with said opening 54 and the atmosphere. The device acts as a drain to prevent

overflowing the carburetor and also helps to lift the mixture into the air at the throttle valve for starting, when the plate 43 is cool, producing an induced flow of the mixture. This provides for easily starting the motor due to the admission of atmospheric air through openings 54 and 55, which immediately mixes with the liquid fuel to supply the motor. The liquid fuel is picked up by the incoming air to form an intimate mixture. When the plate 43 becomes heated, admixture takes place thereon, and said openings only serve to supply additional air.

Opening 15 is provided with an upwardly extending passage 56 (Fig. 2) to prevent any siphoning action of the carburetor float chamber.

I claim:

1. In a carburetor, a mixing chamber, a vacuum controlled valve for controlling the admission of both a liquid fuel and air to the mixing chamber, a heating element, and means for causing a downward flow of both of said fluids into contact with the heating element prior to admixture in said chamber.

2. In a carburetor, a mixing chamber, a vacuum controlled valve for controlling the admission of both a liquid fuel and air to the mixing chamber, means for causing a downward flow of both of said fluids prior to admixture in said chamber, and a heating means onto which the liquid fluid is directly passed prior to admixture, said heating means entering into the conformation of the mixing chamber.

3. In a carburetor, a mixing chamber, a vacuum controlled valve for controlling the admission of both a liquid fuel and air to the mixing chamber including a ported disk element having a hub thereon, a needle valve element, means for causing a downward flow of both of said fluids prior to admixture in said chamber, and a manually operable sleeve having a hub co-acting with the hub on the valve disk for adjusting said needle valve.

4. In a carburetor, a mixing chamber, a valve structure comprising a disk and needle valve elements for respectively controlling the admission of air and a liquid fuel to the mixing chamber, a liquid fuel port controlled by the needle valve, and a vaporizing plate adjacent the mixing chamber and immediately beneath said liquid fuel port onto which said liquid fluid is downwardly directed prior to admixture.

5. In a carburetor, a mixing chamber, a valve structure for controlling the admission of air and liquid fuel to the mixing chamber, said valve structure including a disk element actuated by vacuum and atmospheric pressure to admit a liquid fuel and air in proportional amounts to the mixing chamber, and a vaporizing plate adjacent the mixing chamber onto which said liquid fluid is downwardly directed prior to admixture.

6. In a carburetor, a hollow casing, a hollow head above the casing having a vacuum controlled valve disk therein, a mixing chamber below said casing and in communication therewith, a valve post centrally disposed within the casing, a needle valve movable with the valve disk and within the valve post, a depending apron on the valve disk for varying the supply of air to the casing, a liquid fuel port controlled by the needle valve, and a heating plate within the mixing chamber upon which the liquid fuel is downwardly directed prior to admixture in said chamber.

7. In a carburetor, a mixing chamber, a vacuum controlled valve for controlling the admission of both a liquid fuel and air to said chamber, said valve including a depending needle valve, an inclined heating plate within the chamber, a liquid fuel port immediately above the uppermost portion of the heating plate controlled by said needle valve, whereby the liquid fuel is directed on to said heating plate to flow downwardly thereover by gravity prior to admixture.

8. In a carburetor, a hollow casing, a hollow head above the casing, a mixing chamber below said casing and in communication therewith, air passages between the head and casing, a vacuum controlled valve slidable in the head having an apron thereon for regulating said air passages, a needle valve on the vacuum controlled valve, a liquid fuel port controlled by the needle valve having its discharge opening within the mixing chamber, a heating plate in the mixing chamber and immediately below said discharge opening, and a downward passage of air and liquid fuel through the casing on to the heating plate prior to admixture.

9. In a carburetor, a hollow casing, a hollow head above the casing, a vacuum controlled valve disk in the head having a portion of its under surface subjected to atmospheric pressure, a liquid fuel valve secured to the disk for controlling a liquid fuel port, a depending apron on the valve disk for varying the supply of air to the casing, a mixing chamber below the casing and in communication therewith, and a heating plate within the mixing chamber upon which the liquid fuel and air are downwardly directed prior to admixture.

10. In a carburetor, a hollow casing, a mixing chamber communicating therewith, a vacuum controlled valve for controlling the admission of both a liquid fuel and air to the mixing chamber including a needle valve element, a liquid fuel port controlled by the needle valve, a reservoir for containing a liquid fuel, an arm extending from the reservoir and pivotally secured to the casing, said arm having a passage therein for conveying liquid fuel from the reservoir to the needle valve port, and a heating plate in the mixing chamber.

ber on to which the liquid fuel and air are downwardly directed prior to admixture.

11. In a carbureter, a hollow casing, a hollow head above the casing, a vacuum controlled ported valve disk in the head having a portion of its under surface subjected to atmospheric pressure, a liquid fuel valve on the disk for controlling a liquid fuel port, a depending apron on the disk for varying the supply of air to the casing, a hub on the said disk, a sleeve in the hollow casing, a hub on the sleeve adapted to contact with the hub on the disk, and manually operable means secured to the sleeve for rotating and translating the same to adjust the liquid fuel valve.

In testimony whereof I affix my signature.
VINCENT O. VAN BRIGGLE.
